HOLDER FOR CIGARETTE PACKAGE AND MATCHBOOK

Leon E. Smith, 16142 Princeton, Detroit, Mich. 48221

Filed Feb. 28, 1966, Ser. No. 1,202

Term of patent 3½ years

(Cl. D85—2)

FIG. 1 is a front perspective view of a holder for cigarette package and matchbook showing my new design;

FIG. 2 is a right side elevational view;

FIG. 3 is a front elevational view;

FIG. 4 is a bottom plan view;

FIG. 5 is a top plan view; and

FIG. 6 is a left side elevational view.

I claim:

The ornamental design for a holder for cigarette package and matchbook, substantially as shown.
